Fred J. Hanson,
Attorney.

UNITED STATES PATENT OFFICE.

CHARLES D. SEYS, OF ST. LOUIS, MISSOURI.

IRONING-TABLE.

1,292,380.

Specification of Letters Patent. Patented Jan. 21, 1919.

Application filed June 11, 1917. Serial No. 173,911.

To all whom it may concern:

Be it known that I, CHARLES D. SEYS, a citizen of the United States, residing in the city of St. Louis and State of Missouri, have 5 invented certain new and useful Improvements in Ironing-Tables, of which the following is a specification.

My invention relates to improvements in ironing-tables, and has for its objects, first, 10 to provide an ironing table which is adapted to be supported at one end by means of foldable supporting legs; second, to provide supporting means for the opposite or front end of the ironing-table to permit it to be 15 easily swung into any position or angle with relation to the support; third, to provide means for supporting the ironing-table in an inclined position when placing or removing articles, such for instance, as skirts, or 20 the like; fourth, to provide means at one end of the ironing-table to support a sad-iron in either the horizontal or inclined position of the ironing-table and to further act as a handle for the operator to grasp when 25 swinging the ironing-table into any one of its several positions.

With the above and other objects in view, the invention consists in the novel construction, arrangement and combination of parts 30 as will be more fully described hereinafter and finally pointed out in the claim hereto appended.

Referring to the accompanying drawings forming a part of this specification wherein 35 like characters of reference denote similar parts throughout the several views:

Figure 1, is a plan view of my improved ironing table, showing the means for swingably supporting one end thereof.

40 Fig. 2, is a side elevation of the ironing-table in a folded position.

Fig. 3, is a detail in perspective of one end of the ironing-board showing the sad-iron support and ironing-board handle.

45 Fig. 4, is a side elevation of the ironing-board set up and supported in position, and with a portion of the ironing-board broken away; the dotted lines in Fig. 4 show the ironing-board supported in an inclined position.

50 Fig. 5, is a front end elevation of the ironing-table.

Referring to the accompanying drawings, the reference character 1 designates 55 an ironing-board of any suitable shape, size, or design.

A pair of main supporting legs 2 are hingedly connected, as at 3, to the underface of the ironing-board 1, near the rear edge thereof. The upper end of the supporting 60 legs 2 are united or connected by means of a suitable cross-head 4, and the lower end of each supporting leg 2 is connected by means of the cross-piece 5.

The underface of the ironing-board 1, is 65 provided, near the center thereof, with a cross-cleat 6, having its upper face provided with a suitable recess 7. One end of a suitable resilient locking arm 8, is positioned in the recess 7, and held thereby in 70 fixed engagement with the under-face of the ironing-board 1. The free end of the locking arm 8, is adapted to engage and wedge against the inner front-face of the cross-piece 4, for holding the supporting legs 2, 75 in their operative or open position.

The means for forcing the free end of the locking arm 8, downwardly to the position shown in dotted lines in Fig. 5, so as to permit the supporting legs 2, to be folded under 80 the ironing-board 1, comprises an arm 9, pivoted as at 10, to the front-face of the cross-piece 4. The lower edge of this arm 9, is adapted to engage the top face or one of the upper edges of the locking arm 7, and 85 the free end of the arm 9, is adapted to engage a stop 11, fixed to the cross-piece 4. This stop 11 stops further upward movement of the arm 9, as is manifest. When the free end of the arm 9 is moved to the 90 position shown in dotted lines in Fig. 5, by pressing downwardly upon the arm 9, it will be observed that it releases or disengages the free end of the locking arm 7, from wedged or frictional engagement with the 95 front face of the cross-piece 4, and thereby permits the supporting legs 2, to be folded under the ironing board 1, as clearly shown in Fig. 2.

The front end of the ironing board 1, is 100 provided with a suitable eye, or its equivalent, 12. A suitable hook, or its equivalent, 13, is adapted to pass through and support the eye 12, thereby also supporting the front end of the ironing-board 1, as is manifest. 105 The hook 13, is suitably fixed to any suitable support, such for instance, as a door or window casing, a wall, or any other desirable support. The hook and eye support for the front end of the ironing-board 1, it will be 110 observed, permits the ironing board 1, to be moved into various positions, and, in fact,

may be swung around so as to lie parallel with the wall or support and used as a side table, if desired. The swinging feature of the ironing table renders it possible to move 5 the board into various positions, especially in small or crowded quarters without having to use both hands in the operation, as is manifest.

A pair of auxiliary supporting legs 14, are 10 each pivotally connected at their upper ends, as at 15, to the inner-faces of the supporting legs 2, as clearly shown in Figs. 4 and 5. By means of these auxiliary supporting legs 14, it will be observed that the ironing-board 15 1, may be tilted into the inclined position shown in dotted lines in Fig. 4, and stand in this inclined position unaided by the operator. The auxiliary supporting legs are loosely united, as at 15, so that when the 20 front end of the board 1, is disengaged from its hooked support and moved upwardly, that the legs 14, will, through gravity, gradually assume the position shown in dotted lines in Fig. 4, without the aid of the operator's foot or hands. When the board 1, is lowered to its normal position, the auxiliary supporting legs 14, will automatically return to their normal position between the supporting legs 2 by gravity. The lower ends 25 30 of the auxiliary supporting legs 14, are united or connected by means of a suitable cross-piece 16.

The feature of permitting the board 1, to be adjusted to an inclined position with the 35 front end thereof, as the highest end, and to cause it to stand in this inclined position alone, is very important and essential, as it permits or allows the operator to place a skirt or similar circular garment over the 40 ironing board, 1, or remove it therefrom, as is manifest.

The rear end of the ironing-board 1, is provided with a cutaway portion 17, and provided with a suitable U shaped metallic 45 sad-iron holder or support 18, having the ears 19, which are suitably fixed to the upper face of the ironing board 1.

The extreme rear end of the ironing-board is provided upon its upper-face with a 50 cross-cleat 20, acting as a side stop for a sad-iron designated 21, and, second, acting as a handle for the operator to grasp when moving the ironing-board to various positions.

It will be observed from the foregoing description that the particular construction of 55 this ironing-board does not obstruct the under-face thereof in any manner and render

it difficult to place a circular garment upon the ironing-board and to move it around the board when ironing the same, as is manifest.

The extremely simple construction and convenience of my improved type of ironing-table is readily seen and understood, and the many advantages thereof will readily suggest themselves to those skilled in the art to which it appertains.

I am aware that minor changes may be made in the exact details of construction of my invention without departing from the 70 spirit thereof, hence reserve the right to make any such changes as may fairly fall within the scope of the appended claim when fairly construed.

What I claim is:

In a device of the class described, in combination, an ironing board having a supporting-eye fixed to the front end thereof and adapted for engagement with a supporting hook carried by another member, a pair of 80 main supporting legs hingedly connected at their upper ends to the underface of the ironing board near the rear edge thereof and adapted to fold forwardly, a cross head uniting the upper ends of the supporting 85 legs, a resilient locking arm fixed at one end to the underface of the ironing board in such a manner as to permit the free end thereof to frictionally engage the inner face of the cross-head for holding the supporting 90 legs in their open position, an arm pivotally connected to the inner face of the cross-head and adapted to engage the upper face of the resilient locking arm at its free end when the resilient locking arm is in engagement with the front face of the cross-head, said arm being so arranged that when downward pressure is applied to one end thereof that it will force the free end of the resilient locking arm out of contact with the 100 front face of the cross-head thereby permitting the supporting legs to be folded into their closed position, and a pair of auxiliary supporting legs pivoted at their upper ends to the inner face of the main supporting legs 105 in such a manner that the lower ends thereof will move to a position to the rear of the main supporting legs to assist the main supporting legs in supporting the ironing board when the ironing board is tilted to its 110 inclined position.

In testimony whereof, I have hereunto signed my name to the specification.

CHARLES D. SEYS.
